CLAIM

The ornamental design for a vehicle treatment apparatus as shown and described.

DESCRIPTION

FIG. 1 is a perspective view of a vehicle treatment apparatus showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof; and,

FIG. 8 is an enlarged detail view of the portion designated as **8** in FIG. 4.

The broken lines are for the purpose of illustrating portions of the vehicle treatment apparatus and form no part of the claimed design. The dot-dash broken lines indicated cutoff boundaries for the enlarged detailed portion views and form no part of the claimed design.

The break lines in the drawings indicate that the appearance of any portion of the article between the break lines form no part of the claimed design.

The dot-dash lines in the figures shown outwardly from the location on the canister represent illumination and form no part of the claimed design.
